UNITED STATES PATENT OFFICE.

JOHN L. HUGHES, OF TULSA, OKLAHOMA, ASSIGNOR OF ONE-THIRD TO ISAAC SHULER, OF TULSA, OKLAHOMA, AND ONE-THIRD TO CLAUDE L. BRUCE, OF SEDALIA, MISSOURI.

FEED-WATER APPARATUS.

1,307,403.

Specification of Letters Patent. Patented June 24, 1919.

Application filed January 10, 1919. Serial No. 270,499.

To all whom it may concern:

Be it known that I, JOHN L. HUGHES, a citizen of the United States, residing at Tulsa, in the county of Tulsa and State of Oklahoma, have invented certain new and useful Improvements in Feed-Water Apparatus, of which the following is a specification.

The object of this invention is to provide means whereby a composition employed for preventing incrustation in the water tubes of a steam boiler and other deposits therein will be intimately commingled with the water fed to the boiler prior to its entrance into the boiler. The invention also seeks to provide means whereby the flow of the water and of the cleaning compound may be regulated and it also seeks to provide an apparatus for the stated purposes which will be simple in its construction and arrangement and may be installed in any boiler plant at a low cost.

The invention is illustrated in the accompanying drawings, in which—

25 Figure 1 is a side elevation of a steam boiler and furnace having my improvements connected therewith;

Fig. 2 is an enlarged vertical section of the tank for containing the compound;

30 Fig. 3 is a detail view illustrating a slight modification.

The boiler 1 and the furnace 2 may be of any well-known construction, a steam chest 3 being provided upon the boiler and equipped with a safety valve 4 and a cut-off valve 5 in the usual manner. The water for feeding the boiler is drawn through a supply pipe 6 from any convenient source of supply and is delivered by said pipe into a heater 7 from which it is drawn by a pump 8 through the pipe 9 and then forced through a pipe 10 to the boiler. A blow-off pipe 11 is provided to permit sediment and other matter to be blown from the boiler at intervals or whenever it is desired to shut down the plant. The steam generated in the boiler is carried through a pipe 12 to the engine or other point of use and a branch 13 leads from the said pipe. From the 45 branch 13 a second branch 14 leads to the pump so as to supply the steam necessary to operate the same and a cut-off valve 15 is provided in the said branch 14 to control the flow of steam therethrough. A third branch 16 leads from the main steam branch

55 pipe 13 into the heater 7 and may discharge freely into the same or may terminate in a coil as preferred. The steam admitted into the heater 7 will raise the temperature of the water therein whether it commingles directly with the water or is merely circulated through a heated coil and the condensed steam may be drawn off through the pipe 9 with the feed water. The pipe 13 continues past the branch 16 and has its end carried 60 into the tank 17 containing the cleaning compound and within the tank commingles directly with a coil 18, as shown clearly in Fig. 2. A cut-off valve 19 is provided in the steam pipe 13 below the branch 16 and a 65 cut-off valve 20 is provided in the said branch 16 so as to provide for thorough control of the flow of steam. The coil 18 leads into an outlet pipe 21 which may be carried to any desired point but will preferably be 70 led into the heater 7 so as to discharge the steam into the same and thereby aid in raising the temperature of the feed water.

75 While comparatively few plants at the present time feed water into the boilers 80 without previously heating same, there are plants in which the feed water is not heated. To permit the application of my apparatus to such plants the outlet pipe 21 may be carried downwardly, as shown at 23 in Fig. 3, 85 so as to communicate directly with the pipe 24 constituting the inlet pipe for the pump, the feed water pipe 25 communicating with the down-turned portion 23, as shown in said Fig. 3. The steam exhausting from the tank 90 will, consequently, act directly upon the feed water within a small compass so as to be thoroughly commingled therewith and will consequently serve to raise the temperature of the same before it enters the boiler. 95

The tank 17 may be constructed of any desired material and may be of any preferred capacity. From the lower end of the same an outlet pipe 26 leads to the pipe 9 and this outlet pipe is controlled by a cut-off valve 27 as will be readily understood, a tube 28 of transparent material being interposed between the valve and the pipe 9 so that the flow to said pipe will be visible and the volume of the cleansing fluid passing to 100 the feed water may be known. The cleaning compound is deposited in a hopper 29 which is disposed above the tank and communicates with the upper end of the same through a 105 spout or tube 30 in which is disposed a con- 110

trolling valve 31. A vent 32 is provided at the top of the tank so that, when the tank is being filled, the trapped air may be permitted to escape and undesirable accelerated feeding of the compound to the feed water will be avoided. A gage tube 33 is provided on the side of the tank so that the height of the liquid therein may be known and a clean out manhole 34 is also provided near the lower end of the tank. It sometimes happens that the tank must be located below the level of the water in the heater or the level of the fluid in the tanks gets lower than the level of the water in the heater, as a result of which condition the feed of the compound is uncertain and so slow that the desired results are not obtained. To avoid such retarded flow, I provide a short nozzle 35 which leads from the pipe 13 into the tank near the upper end thereof and is equipped with a cut-off valve 36. If the valve 36 be opened, steam will be admitted to the tank above the level of the liquid therein and will exert sufficient pressure upon the liquid to accelerate the flow of the same and obtain the desired results.

It is thought the operation of the apparatus is evident from what has been said. The composition or cleaning fluid is fed into the tank from the hopper thereon and the valve 27 is set to permit escape of the fluid from the tank at the desired speed. The pump 8 will be operated by steam generated in the boiler and will suck water through the pipe 6, the heater 7, and the pipe 9 and will also suck some of the cleaning compound from the tank 17 through the pipes 26 and 28, this cleaning fluid being thoroughly commingled with the feed water in its passage through the pipe 9, the pump and the pipe 10, so that when the water enters the boiler it will be saturated with the cleaning liquid and there will be no incrustation upon the water tubes and all other deleterious deposits will be prevented. The coil 18 within the tank serves to heat the liquid so that it will not be permitted to thicken but will be kept in the proper condition to flow easily and readily through the several pipes and will also be raised in temperature so that it will aid in raising the temperature of the feed water. Even in those plants which are not equipped with preheaters the use of my

apparatus will raise the temperature of the feed water sufficiently to accelerate the formation of steam and consequently effect an economy of fuel. The apparatus does not occupy a large space and may be readily installed in plants now in use. The tank may be placed at any point on the water line between the source of water supply and the boiler, the steam pressure being sufficient to inject the compound into the feed water and effect the commingling of the same.

Having thus described the invention, what is claimed as new is:

1. In an apparatus for the purpose set forth, the combination of a feed water supply pipe, a container for a cleaning compound in communication with said pipe, and a steam pipe in communication with the feed water supply and having a portion of its length disposed within the said container.

2. In an apparatus for the purpose set forth, the combination of a feed water supply pipe, a steam pipe, a tank to contain a cleaning compound, a coil within the tank connected with the steam pipe, and means whereby steam from said pipe may be caused to act on the feed water.

3. In an apparatus for the purpose set forth, the combination of a feed water heater, a pipe leading therefrom, a container for a cleaning compound in communication with said pipe, a steam supply pipe, a branch from said pipe leading into the feed water heater, a coil disposed within the container and connected with the steam pipe, and a pipe leading from the coil to the feed water heater.

4. In an apparatus for the purpose set forth, the combination of a feed water heater, a container for a cleaning compound, a hopper on said container, a valve controlling the flow from the hopper into the container, a feed water pipe leading from the feed water heater, a valved pipe leading from the container into the said feed water pipe, a steam pipe having a branch leading into the feed water heater and having another branch disposed within the container, and a pipe leading from the last-mentioned branch into the feed water heater.

In testimony whereof I affix my signature.

JOHN L. HUGHES. [L. S.]
